CABLE BENDING TOOL

Ignazio Leonardo, Mountainside, N.J., assignor to The Thomas & Betts Co., Elizabeth, N.J., a corporation of New Jersey

Filed Aug. 31, 1961, Ser. No. 66,573

Term of patent 14 years

(Cl. D54—13)

FIG. 1 is a perspective view of a cable bending tool showing my new design, a portion of the handle shown being broken away to illustrate indeterminate length.

FIG. 2 is a view in elevation of the back side of the head portion thereof;

FIG. 3 is a view in elevation of the opposite open side of the head portion thereof; and

FIG. 4 is an end view in elevation of the head portion of the cable bending tool.

The dominant features of my design reside in the portions shown in full lines.

I claim:

The ornamental design for cable bending tool, as shown and described.
